DETACHABLE CORNER STRUCTURE FOR CRATES

Edward M. Pennock, Minneapolis, Minn., and
Elmer W. McClelland, Hollywood, Calif., as-
signors to G. H. Tennant Company, Minne-
apolis, Minn., a corporation of Minnesota

Application May 5, 1930, Serial No. 449,753

8 Claims. (Cl. 217—12)

Our invention relates to crates particularly those designed to be used as bottle crates where portions of the same are made of metal reinforcing strips, such as the corners, bottom rails and 5 stacking arms, and the sides and ends of which are made of wooden slats.

In the handling of these milk bottle crates they must stand considerable wear and tear and it sometimes happens that some of the wooden slats 10 will be broken and then it is necessary that the crates be repaired and we have designed a means of permitting the repair to be made easily and quickly and without an expensive structure where it is necessary to cut off all of the rivets which 15 hold the parts together. We accomplish this by providing the corner member with openings and slots for some of the rivets so that it is only necessary to cut off two of the holding rivets at the bottom, and then the corner member can be 20 slid downward so as to release the same from the other rivets. This structure permits any of the slats to be replaced very readily.

It is also a feature of our invention to provide a bottle crate wherein the same can be readily 25 disassembled for repair by sliding one of the members, that hold the slats, in relation to the other at the corners.

It is also a feature to provide a crate made up 30 of a series of superimposed slats to provide the sides and ends of the same wherein the complementary groove is formed in each slat which is adapted to co-operate with the groove of the adjacent slat to receive a longitudinally extending edge tongue of a corner member to permit 35 the corner member to be slid into and out of operating position. This structure with rivet engaging openings formed in the corner member provides a means of quick disassembling of the crate.

40 These features together with other details and objects of the invention will be more clearly and fully set forth in the specification and claims.

In the drawings forming part of our specifica- 45 tion:

Figure 1 is a perspective view of our milk bottle crate, showing our detachable corner holding means in operative position.

Figure 2 is an enlarged detail in side eleva- 50 tion of one of the corners of our crate.

Figure 3 is a section on the line 3—3 of Fig- ure 2.

Figure 4 is an enlarged perspective detail of one 55 of the corners of our crate, showing the outer corner member removed.

Figure 5 illustrates a perspective view of the removed corner member used in our crate.

Figure 6 illustrates a section of a detail of a portion of our crate.

In the drawings our crate A is designed to be 5 used primarily as a milk bottle crate and is provided with spacing means by wires 10 and 11 to form bottle compartments such as are illustrated in our co-pending application, Ser. No. 143,611.

The crate A is made up of a series of wooden 10 slats 12 which form the ends of the crate, while the wooden slats 14 form the sides of the crate.

The slats 12 and 14 are superimposed one above the other and are ordinarily spaced slightly apart so as to permit for the swelling and 15 contracting of the wood in the use of the crate A. The milk crates such as A are usually used to hold the bottles while they are run through the washing machine, and thus the crates A are subject to moisture so that they must be 20 constructed to withstand this use, together with the severe usage to which they are subjected in handling when they are filled with milk bottles and stacked one upon the other.

The slats 12 and 14 are held together at 25 their ends to form the corners of the crate A by the inside stacking arm 15 which is formed with a stacking lug 16 on the top thereof and by means of the right angular shaped outer corner 30 members 17.

The outer corner members 17 are formed with a longitudinal inwardly extending flange 18 which is adapted to extend into the slots 19 formed in each of the slats 12 and 14 so as to assist in holding the slats in line and to hold the same together 35 while the inside corner member 15 and the outside corner member 17 are secured together by the rivets 20 and 21. In fastening the members 15 and 17 together by the rivets 20 and 21, we have found that in the usual size crate the slats 40 12 and 14 are so positioned that the upper slats 12 and 14 are held by the upper rivet 20, and then a center slat is held by another rivet 20, while the bottom slat is held by the rivet 21. This provides a structure of the crate A where the intermediate slats 14' for assembling are freely 45 disposed between the regular slats or the upper center and lower slat, such as is illustrated in Figure 3.

Thus the crate A is made with the slats spaced 50 sufficiently apart from each other to permit the expansion and contraction of the same. The wooden slats form the best side walls for the crates A because they are tough, long-wearing, when made of the right kind of wood, and act 55

as an insulating means against shock in one crate bumping against the other, and act to protect the bottles in the crate to prevent breaking to a very large degree.

- 5 The outer corner member 17 is clearly illustrated in Figure 5 and is formed with enlarged openings 22 for the heads of the rivets 20. From the opening 22 we provide a slot 23 which is adapted to engage the shank of the rivets 20.
- 10 The lower rivet 21 is adapted to pass through the openings 24 formed in the corner 17 and it will be noted that the corner 17 is formed with upwardly inturned flange members 25 which overlap the lower end of the inner or corner member 15. The 15 openings for the respective rivets in the member 15 are of a simple hole to receive the shank of the rivets 20 and 21, respectively.
- In Figure 6 we have illustrated a removable pin or bolt 28 which is held in position by the lock 20 nut 29. By removing this bolt the outer locking member 17 which locks over the heads of the rivets 20 may be held against longitudinal movement so as to lock the ends of the slats together at the corners and to connect the inner member 15 with the member 17 to form a rigid corner for the crate A.

In assembling our crate the slats 12 and 14 are formed with suitable openings for the rivets in the proper slats and the transverse grooves 19 30 into which the flange 18 is adapted to fit. The members are placed in the proper position and the rivets are upset to rivet the members 15 and 17 over the ends to form the reinforcing corners of the crate A. Should it become necessary 35 to replace one of the slats of the crate A, such as 12 or 14, it is only necessary to cut off the head of the rivets 21 and drive the outer corner member 17 downward so that the upset heads of the rivets 20 may pass through the openings 22. The crate 40 can thus be disassembled and repaired, after which it is only necessary to slip the corner member over the heads of the projecting rivets 20 and to slide the corner member 17 back into position so that the slots 23 engage the shanks of the 45 rivets 20, and then new rivets 21 placed through the members and slats to lock them into position. Thus the rivets 21 virtually become lock rivets to hold the members 15 and 17 in place and against longitudinal movement and by cutting off these 50 rivets the crate can be readily disassembled. We have found in the manufacture of milk bottle crates that this structure is very desirable and that it is a great saving in the repairing and assembling of milk bottle crates.

55 In accordance with the patent statutes we have described the construction and operation and principles of our milk bottle crate and while we have illustrated a particular design and structure for the purpose of permitting the 60 easy disassembling of the crate parts for repair or replacement, we desire to have it understood that the same is only suggestive of a means of carrying out our invention and that other uses and adaptations may be apparent to those skilled 65 in the art without departing from the spirit of the invention within the scope of the following claims.

We claim:

1. A corner structure for slat crates including 70 relatively slideable inner and outer corner members, means extending through said corner members for holding said corner members assembled together, means in one of said corner members for slidably releasing said one corner member, and locking means connecting said inner and

outer corner members whereby the corner assembly may be disassembled by releasing said locking means and sliding said one corner member.

2. A bottle crate including a series of superimposed slatted members forming the walls thereof, relatively slideable inner and outer corner members for holding said slatted members in position relative to each other, rivet means connecting said corner members together, means releasably securing said rivets to said corner members, and means securing said rivets from releasing.

3. A crate having a series of wooden slats adapted to form the walls thereof, a corner assembly for said slats including an inner reinforcing stacking arm, an outer reinforcing locking corner, transverse slots in each of said slats, and a longitudinal flange adapted to slide into said slots to lock the slats in said outer corner member, means connecting said inner stacking arm and said outer locking corner together, means holding said outer corner member releasably to said connecting means, and locking means connecting said inner arm and said outer corner member holding said outer corner member from releasing from said connecting means.

4. A crate having a series of wooden slats adapted to form the walls thereof, relatively slideable inner and outer right angular corner members, rivet means connecting said inner and outer corner members together, means on said outer corner member releasably engaging said rivets, disengageable from said rivets by relatively sliding said outer corner member, and locking rivet means holding said corner members from relative sliding.

5. A crate having a series of wooden slats adapted to form the walls thereof, relatively longitudinally movable inner and outer corner members, means on one of said corner members 40 for locking the slats of two adjacent crate walls against longitudinal movement, locking pins for holding said corner members against longitudinal movement, and means detachably engageable with said outer corner member including means 45 on said outer corner member normally engaging said engaging means.

6. A bottle crate including, side walls, a corner reinforcing member, said reinforcing member having key-hole shaped slots therein, securing 50 means for securing said corner member to said crate removably engaging in said key-hole slots, and locking means for locking said corner member against slideable disengagement with said securing means.

7. A bottle crate including a series of superimposed slats, a corner reinforcing member, means for securing said corner reinforcing member to said slats, means on said corner member detachably engaging said securing means, and 60 means for locking said corner member from disengagement.

8. A corner lock for slatted milk bottle crates including a pair of relatively disengageable inner and outer corner members, means cooperable 65 with said outer corner member for detachably connecting said members together and for holding the slats in proper relationship, said outer corner member including means engageable with said first named means to permit one member 70 to be slidably disengaged from the other, to disassemble the corners of the crate for repair when it is so desired.
